UNITED STATES PATENT OFFICE.

LYMAN R. ROBERTS, OF RUTHERFORD, NEW JERSEY, ASSIGNOR TO UNDERWOOD TYPE-WRITER COMPANY, OF NEW YORK, N. Y., A CORPORATION OF DELAWARE.

TYPE-WRITING MACHINE.

1,177,140.

Specification of Letters Patent. Patented Mar. 28, 1916.

Application filed May 14, 1913. Serial No. 737,499.

To all whom it may concern:

Be it known that I, LYMAN R. ROBERTS, a citizen of the United States, residing in Rutherford, in the county of Bergen and State of New Jersey, have invented certain new and useful Improvements in Type-Writing Machines, of which the following is a specification.

My invention relates to typewriting machines constructed and adapted for use as billing machines, or for work where it is desirable to support work-sheets of different characters on the platen to receive a common record, or to permit the relative positions of the work-sheets on the platen to be changed.

A feature of the invention is the provision of means to support on a rotary platen superposed work-sheets of different characters, as, for example, ledger sheets, statement sheets, and proof sheets, with interposed manifolding sheets, independent holding means being provided for the inner and outer work-sheets to permit adjustment or changes in their relative position on the platen.

The platen, as shown, is in the form of the section of a cylinder, with a printing area sufficient to accommodate a large work-sheet such as a ledger sheet, and it is provided along its opposite edges with independently operable clamps or holders for the work-sheets, so that the sheet or sheets may be supported on the platen and held by the clamps along one edge of the platen, and superposed work-sheets may be held by the clamps along the other edge; the arrangement permitting independent adjustment of the sheets. The clamps project through openings in the platen and are adapted to be lifted into position to receive the work-sheets. The work-sheets are each provided along one or both edges with notches spaced to correspond with the rulings on the paper, the clamps being suitably spaced to enter the notches and having overhanging ends to grip the work-sheet. This arrangement serves to aline the work-sheet and permits its adjustment in line-space direction through distances corresponding to the rulings on the sheets, and holds the latter with the rulings on the superposed sheets directly under each other. The platen is rotatably mounted on a traveling carriage driven by a spring motor, the letter-feed travel of the carriage being controlled

by an escapement mechanism actuated from the type keys, which also actuate the type bars in the usual manner.

Other features and advantages will hereinafter appear.

In the accompanying drawings, Figure 1 is an end elevation view of a typewriting machine constructed in accordance with the principles of my invention. Fig. 2 is a detail sectional view illustrating the clamps for the work-sheets, and the means to actuate the clamps. Fig. 3 is a part sectional front elevation view of the machine. Fig. 4 is a sectional view taken longitudinally of the platen and illustrating the clamps and the way in which the work-sheets are placed in position. Fig. 5 is a detail view of one of the clamps. Fig. 6 is a detail view showing the line-space mechanism.

The platen 1 is rotatably mounted in a traveling platen frame or carriage 2 driven by a spring motor 3 connected through a band 4 to the carriage. Bearing lugs 5 on the platen frame are slidable on a stationary carriage rail 6 on the machine frame 7. The front of the platen frame has a bearing roller 8, which runs on a stationary guide rail 9. The platen axle 10 is seated in bearings 11, and leaf springs 13 bearing on the upper surface of the platen axle serve to prevent accidental displacement of the platen. The platen may be rotated by means of hand wheels 14 on the ends of the platen axle, or any suitable form of line-space mechanism.

As herein shown, the line-space mechanism comprises a lever 15 pivoted at 16 to the platen frame and having at its rear end a pivoted spring-pressed pawl 17 co-operating with a rack 18 on the left-hand end of the platen, the pawl 17 having a finger-piece 17a for lifting the pawl from the rack. The lever 15 is normally held in the position shown in Fig. 1 by a spring 19. When the free end of the lever is depressed, it is carried to the position shown in Fig. 6, the platen being rotated with it a distance of one line-space. As the lever returns, the pawl rides idly over the rack and engages the next lower tooth of the rack. The platen is held against accidental rotation by means of a spring detent 20 having a curved end 21 which is held between adjacent rack teeth, as shown in Fig. 3.

The platen is preferably in the form of a

section of a cylinder, and as herein shown is substantially semi-cylindrical. It will be understood that the platen surface may extend through a greater or less arc, and in some instances may form a complete cylinder. The platen is of large diameter, so that the printing area is sufficient to accommodate any work-sheet it may be desired to place thereon. The radius of curvature is 10 also preferably large, so that it is not necessary to bend or curve the work-sheet sufficiently to prevent it from readily conforming to the platen surface, and to facilitate the positioning and clamping of the work-sheet. The machine is particularly adapted for keeping accounts where several sheets of different characters are grouped together, and the same record made on all the sheets by a single printing operation. For example, a ledger sheet 22 is placed in position 15 on the platen, and over this may be placed a statement sheet 23, and a proof sheet 24, manifolding sheets or carbons 25 being interposed between the work-sheets.

25 The means for holding the work-sheets in position comprises clamps 26 extending through the platen and having offset ends 27 which overhang the work-sheets and clamp them against the surface of the platen. The clamps are held in clamping position by springs 28. Each set of clamps is arranged in an arc of a circle, there being one set of clamps adjacent each end of the platen. Each set of clamps is released by 30 means of an arc-shaped bar 29 having cam surfaces 30 to engage the clamps and lift them to releasing position.

35 The cam bar 29 is mounted on the under side of the platen by means of brackets 31 secured to or formed integral with the bar and slidably held against the inner face of the platen by shouldered screws 33 extending through slots 34 in the brackets and threaded into the platen. An arm 35 on the 40 cam bar projects through a slot 36 in the platen, and has a knob or handle 37 for operating the bar. When the handle 37 is moved forward into the position shown in Fig. 2, the cams 30 lift the clamps 26, as shown in 45 Fig. 2 and the right-hand end of Fig. 4. When the clamps are thus lifted, a work-sheet may be placed on the platen and moved laterally, as indicated by the arrow (Fig. 4), into position, the clamps entering notches 50 38 in the edge of the work-sheet. The handle 37 may now be moved backward to release the cams from the clamps and allow the springs 28 to pull the clamps inward, so that their overhanging ends 27 grip the 55 work-sheet, as indicated at the left-hand end of Fig. 4. The notches 38 are preferably equally spaced and at equal intervals with the rulings on the work-sheet. The 60 distance between these notches is also preferably the same as the distance between ad-

jacent teeth of the rack 18. It will be seen that by this arrangement the adjustment of any work-sheet either up or down on the platen is always through a distance equal to one or more line-spaces, and the ruled lines 70 on each superposed sheet will be directly over the lines on the sheet or sheets beneath it.

75 The printing of the work-sheets is effected by types 39 and type bars 40 pivoted on a curved fulcrum rod 41 and actuated by finger-keys 42 on key levers 43 connected through bell crank levers 44 to their type bars. The levers 43 are pivoted at 45, so that when a finger-key is depressed the corresponding bell crank 44 operates to throw its connected type bar up to printing position in front of the platen. The type bars may be arranged in a well known manner 80 in an arc-shaped or quadrant frame 40^a.

85 The letter-feed movement of the carriage is controlled by an escapement mechanism comprising an escapement wheel 46 driven by a pinion 47 in mesh with a rack 48 on the carriage. Escapement dogs 49 and 50, which 90 rock on a fulcrum 51, are connected through a link 52 to an arm 53 on a rock shaft 54 to which are also secured rock arms 55 carrying a universal bar 56, actuated by shoulders 57 on the type bars.

95 The rack 48 is carried on arms 58 pivoted at 59 to the platen frame. An arm 60 connected to an arm 58 (Fig. 1) is connected through a link 61 to a lever 62 having a finger-piece 63 which, when depressed, operates to lift the rack 48 free of the pinion 47, permitting the carriage to be moved 100 freely in either direction. A pointer 64 working over a scale 65 may be provided, if desired. Spring-pressed arms or wings 66 may be placed, if desired, on opposite sides of the printing point to guide and hold the work-sheet against the platen at the printing point.

105 Variations may be resorted to within the scope of the invention, and portions of the improvements may be used without others.

Having thus described my invention, I claim:

110 1. In a typewriting machine, the combination with a rotary platen and types to strike thereagainst, of a series of paper-gaging clamps arranged in the arc of a circle adjacent one end of the platen and forming a means to square work-sheets to the printing line and gage them with respect to their positions circumferentially of the platen, and a manually-operable clamp-operating device located within the platen 115 and controlling the clamps for clamping or releasing the work-sheets while the platen is at rest.

120 2. In a typewriting machine, the combination of a rotary platen and types to print thereon, a clamp for a work-sheet, said 125

- clamp extending through the platen in position to grip the work-sheet, and a clamp-actuating device slidably mounted on the inner surface of the platen and manually operable while the platen is at rest to actuate the clamp.
3. In a typewriting machine, the combination with a rotary platen and types arranged to print thereon, of a work-sheet holding clamp projecting through the platen, a spring to move the clamp to sheet-holding position, and a clamp-operating device slidably mounted on the inner surface of the platen and formed with a cam operable while the platen is at rest to move the clamp to sheet-releasing position.
4. In a typewriting machine, the combination of a rotary platen arranged for types to strike thereagainst, a clamp projecting above the surface of the platen and adapted to grip a work-sheet and hold it in position on the platen for the types to print thereon, a spring to hold the clamp in gripping position, a cam beneath the platen surface, and a clamp-operating device slidably mounted on the inner surface of the platen and manually operable while the platen is at rest for moving the cam into position to release the clamp.
5. In a typewriting machine, the combination of a platen having a curved surface, a row of work-holding devices arranged in an arc on said surface, and a cam device mounted on the inner surface of the platen and movable in an arc to actuate said holding devices.
6. In a typewriting machine, the combination of a platen having a curved surface, clamping devices thereon arranged in the arc of a circle, and an arc-shaped clamp-actuating device mounted on the inner surface of the platen and slidably thereon to actuate the clamping devices.
7. In a typewriting machine, the combination of a rotary platen, a series of clamps, and a bar slidably connected to the inner surface of the platen and provided with means to actuate the clamps.
8. In a typewriting machine, the combination of a rotary platen, a series of clamps, and a bar slidably connected to the inner surface of the platen and provided with cams to project the clamps for releasing the work-sheets.
9. In a typewriting machine, the combination with a rotary platen, of a series of work-sheet holding clamps projecting through openings in the platen, springs to move said clamps inward to clamping position, an arc-shaped cam bar slidably mounted on the inner surface of the platen and formed with cams to project the clamps, and a handle connected to the cam bar and projecting beyond the platen.
10. In a typewriting machine, the combination of a rotary platen, line-space mechanism for rotating the platen through predetermined angles, and a series of work-sheet holding devices located at angular distances on the periphery of the platen, each equal to a whole number of times the angular distance through which the platen is rotated by each operation of the line-space mechanism.
11. In a typewriting machine, the combination of a rotary platen, an arc-shaped series of clamps arranged along one end of the platen and having overhanging ends adapted to engage the edge of a work-sheet and clamp it against the platen, means on the inner side of the platen for individually holding the clamps in clamping position, and a clamp-releasing device within the platen operable to move the clamps to position to release a work-sheet.
12. In a typewriting machine, the combination of a rotary platen having a printing surface for the types to strike against, a series of clamps arranged in an arc along the end of the platen to clamp the lateral edge of a work-sheet and hold it on the printing surface of the platen, each of said clamps movable in a direction perpendicular to the face of the platen into and out of clamping position, springs to individually move the clamps to clamping position, and a releasing device located within the platen and operable manually to actuate the series of clamps collectively to work-sheet-releasing position.
13. In a typewriting machine, the combination of a rotary platen having a printing surface arranged for types to strike against, independently operable work-sheet holding clamps carried by the platen and arranged in rows adjacent opposite ends thereof to clamp the lateral edges of work-sheets and hold said sheets on the printing surface, and clamp-releasing devices slidably mounted on the inner surface of the platen and manually operable while the platen is at rest, to move the clamps into position to release the work-sheets.
14. In a typewriting machine, the combination with a rotary platen and types arranged to strike thereagainst, of work-sheet-holding devices formed to engage cooperating holding surfaces on work-sheets to hold a plurality of the work-sheets on the printing surface of the platen, and permitting relative adjustment of the work-sheets through distances determined by the spacing of the work-sheet-holding devices and of said holding surfaces, thereby permitting the work-sheets to be arranged said distances one in advance of another on the platen.
15. In a typewriting machine, the combination with a rotary platen, of a series of work-sheet holding clamps, and line-space mechanism comprising a line-space rack.

having teeth arranged around the platen axle; the angular distances between adjacent clamps each being a whole number of times the angular distance between adjacent teeth of the rack.

5 16. In a typewriting machine, the combination of a rotary platen arranged for the types to strike against and having a printing surface with a long radius of curvature 10 to form a collating board on which work-sheets may be arranged, clamping means along the lateral edge of the platen surface to engage the lateral edges of work-sheets and hold them in position on the platen to 15 be written upon, said clamping means extending within the platen, and a manually operable operating device mounted on the inner surface of the platen for operating said clamping means while the platen is at 20 rest.

17. In a typewriting machine, the combination with a rotary platen having a curved surface forming an incomplete cylinder of large diameter to form a collating board or 25 table on which work-sheets may be arranged, a series of clamps arranged in a row along the curved edge of the platen to engage the edge of a work-sheet placed on the platen, said clamps extending through the 30 platen surface, springs to individually move the clamps to work-sheet holding position, and a manual releasing device to collectively move the clamps while the platen is at 35 rest into position to release the work-sheets.

18. In a typewriting machine, the combination with a rotary platen having a curved surface forming an incomplete cylinder of large diameter to form a collating board or 40 table on which work-sheets may be arranged, a series of clamps arranged in a row along the curved edge of the platen to engage the edge of a work-sheet placed on the platen, said clamps extending through the 45 platen surface, springs to individually move the clamps to work-sheet holding position, and a manual releasing device slidably mounted on the inner surface of the platen and operable while the platen is at 50 rest, said releasing device comprising cams to engage the clamps and move them to work-sheet releasing position when the releasing device is operated.

19. In a typewriting machine, the combination with a rotary platen having a curved surface of large diameter to form a collating table on which work-sheets may be arranged while the platen is stationary, sheet-gaging clips carried by the platen and arranged to 55 engage the work-sheets at different points along a side edge thereof, square the sheets to the printing line, gage them both circumferentially and lengthwise of the platen, and clamp them in position on the platen, a carriage on which the platen is mounted, letter-

feed mechanism controlling the travel of the carriage, and line-spacing mechanism to effect line-space rotation of the platen.

20. In a typewriting machine, the combination with a substantially semi-cylindrical rotary platen of large diameter forming a work-sheet holding surface of sufficient extent to receive a full-size work-sheet thereon and permit the entire printing area to be brought within the printing zone during an incomplete rotation of the platen, and work-sheet holding clips carried by the platen and arranged to engage the work-sheets at different points along the lateral edges thereof and gage the sheets both circumferentially and lengthwise of the platen, said clips operable to clamp the work-sheets in their gaged position on the platen. 70 75 80

21. In a typewriting machine, the combination with a rotary platen having a curved surface, of a series of work-sheet holding clamps arranged in a row on said platen in position to clamp the lateral edge of a work-sheet, each clamp comprising a stem extending through the platen and an overhanging projection to engage and clamp a work-sheet to the platen, springs within the platen to individually move the clamps to clamping position, and a clamp-releasing device on the inner surface of the platen and having a sliding connection with the platen, said device formed with cams to engage the clamps and project them to releasing position, said releasing device having a handle projecting beyond the platen for operating said device. 85 90 95 100

22. In a typewriting machine, the combination with a machine frame and a carriage thereon, of a rotary platen mounted on the carriage, the portion of the platen above its axle being above the machine frame and carriage and presenting an area of sufficient extent to form a collating table on which may be arranged a main ledger or analogous sheet and other sheets or forms of smaller size overlying one another in different positions on the table, with the supporting area of the table underlying the entire surface of the sheets, and sheet-gaging clamps arranged to gage the sheets circumferentially of the platen and operable to clamp the sheets in their gaged position. 105 110 115

23. In a typewriting machine, the combination of a segment of such large curvature and area as to form a sheet-collating table, permitting the assembling thereon while in one position, of a main ledger or analogous sheet and various sheets or forms of smaller size overlying one another in different relationships with the table, and means on said table to engage the side edges of the sheets to gage them in the direction of their length, with the sheets in different positions of advancement with respect to the printing line, and to square the sheets 120 125 130

- to the printing line and hold them in their adjusted positions; said table being mounted upon a pivot to be moved in line-spacing direction relatively to the types, and being 5 curved concentrically with said pivot for said movement, and having a printing field to support the work-sheets when struck by the types, whereby the table may serve as a combined collating table and platen.
- 10 24. In a typewriting machine, the combination of a segment of such large curvature and area as to form a sheet-collating board or table permitting, while in one position, the assembling thereon of a main ledger or 15 analogous sheet, and other sheets or forms overlying one another in different positions on the table; means on said table to engage one side edge of one or more of said sheets, to gage them in the direction of their length, 20 to square them to the printing line and to hold them in their adjusted positions; means to engage the opposite side edge of another sheet, to gage it in the direction of its length, to square it to the printing line and to hold 25 it in its adjusted position; so that each sheet is retained in position on the table by sheet-engaging means along at least one of its side edges; releasing devices for releasing the engaging means along one side independently 30 of those along the other side, and a carriage on which said table is rotatably mounted, the surface of said table being curved concentric to its axis of rotation and having a printing field to support the work-sheets when struck 35 by the types, whereby the table may serve as a combined collating table and platen.
25. In a typewriting machine, the combination of a segment of such large curvature and area as to form a sheet-collating table 40 permitting the assembling thereon while in one position, of a main ledger sheet and other sheets or forms overlying one another in different positions on the table, a carriage on which the table is rotatably mounted, the 45 surface of the table being curved concentric to its axis of rotation and having a printing field to support the work-sheets when struck by the types, the table thereby serving as a combined collating table and platen, the carriage having a letter-feed movement in a direction parallel with said axis of rotation; and sheet-justifying clips arranged to engage a side edge of the sheets, to gage the sheets with their leading edges at different 50 positions of advancement, to square the sheets to the printing line, and to clamp the sheets in their justified positions on the table.
- 55 26. In a typewriting machine, the combination of a segment of such large curvature and area as to form a sheet-collating table 55 permitting the assembling thereon while in one position of a main ledger sheet and other sheets or forms overlying one another in different positions on the table, a carriage on 60 which the table is rotatably mounted, the 65 surface of the table being curved concentrically to its axis of rotation and having a printing field to support the work-sheets when struck by the types, the table thereby serving as a combined collating table and platen, the carriage having a letter-feed movement in a direction parallel with said axis of rotation; a series of sheet-gaging and clamping devices carried by the table and projecting upwardly therefrom in position to 70

engage corresponding gaging surfaces along the side edge of the sheets and thereby square said sheets to the printing line and gage the sheets with respect to their position of advancement in the direction of their length, said clamps movable downwardly after the sheets have been gaged thereby into clamping position to hold the sheets in their ad-

justed position on the table, and a clamp-releasing device carried by the table and operable to collectively actuate the clamps to sheet-releasing position. 10
